UNITED STATES PATENT OFFICE.

ELLWOOD IVINS, OF PHILADELPHIA, PENNSYLVANIA.

JOINT-PIECE FOR ELECTRICAL CONDUCTORS.

SPECIFICATION forming part of Letters Patent No. 586,439, dated July 13, 1897.

Application filed November 11, 1896. Serial No. 611,732. (No model.)

To all whom it may concern:

Be it known that I, ELLWOOD IVINS, a citizen of the United States, residing in Philadelphia, Pennsylvania, have invented certain 5 Improvements in Joint-Pieces for Electrical Conductors, of which the following is a specification.

The object of my invention is to provide a joint-piece for electrical conductors which is 10 of light weight, can be cheaply manufactured, can be readily applied to the wires to be joined, and will insure good electrical connection between said wires, and this object I attain in the manner hereinafter set forth, 15 reference being had to the accompanying drawings, in which—

Figure 1 is a perspective view of a joint for electrical conductors made in accordance with my invention. Fig. 2 is a plan or top 20 view of the same. Fig. 3 is a transverse sectional view on a larger scale. Fig. 4 is a view illustrating the course taken by the end portion of each of the wires. Fig. 5 is a perspective view illustrating another form of joint 25 made in accordance with my invention. Fig. 6 is a transverse section of the same on a larger scale, and Figs. 7, 8, and 9 are views illustrating modifications of my invention.

In carrying out my invention I prefer to 30 take a seamless tube or tube-blank and draw the same so as to indent its sides and form a joint-piece with three independent tubes or tubular receptacles 1, 2, and 3, the tubes in the joint-piece shown in Fig. 1 being disposed 35 in triangular form—that is to say, two being side by side in the same plane and the other above and midway between these two.

In making a joint or connection with this joint-piece one of the wires, say the wire 4, is 40 passed through the tube 1 in one direction, say from the right, and the other wire 5 is passed through the tube 2 in the opposite direction, the end portion of each wire being permitted to project for some distance beyond the end of the tube through which it is passed. The end portion of the wire 4 is then passed 45 over the wire 5, bent back upon itself, and thrust into one end of the tube 3, and the end portion of the wire 5 is passed under the wire 4 and then bent back upon itself and thrust 50 into the opposite end of said tube 3, after which the wires are drawn tight, so as to pull

their loops 6 close up to the ends of the joint-piece. This has the effect not only of causing the loop of the wire 4 to bear firmly against 55 the wire 5 and the loop of the wire 5 to bear with equal force against the wire 4, but it also draws the said wires firmly into contact with the end portions of the tubes to which they are adapted, hence insuring a good electrical contact independent of the contact of the wires with the tubes between the ends of the latter, so that perfect electrical connection between the two wires is insured. 60

In Figs. 5 and 6 I have shown a joint-piece 65 in which the three tubular portions 1^a, 2^a, and 3^a are disposed side by side in the same plane instead of being arranged triangularly, as shown in Figs. 1, 2, and 3, the course of the wires, however, being substantially similar in 70 both cases.

In Fig. 7 I have shown a triple tube with joint, and in Fig. 8 I have shown three separate tubes secured together by soldering or brazing; but I prefer in all cases to form the 75 triple tube from a single seamless-tube blank.

While I also prefer in every case to dispose the wires in the manner described, so that a loop of each wire will press firmly upon the other wire, such disposal is not absolutely essential to the broadest embodiment of my invention. For instance, one wire may pass through the tube 1 and have its end portion bent backward into one end of the tube 2, and the other wire may pass through the tube 85 3 and have its end portion bent back into the opposite end of said tube 2, as shown in Fig. 9, neither wire crossing the other.

Having thus described my invention, I claim and desire to secure by Letters Patent—

1. A joint-piece for electrical conductors, said joint-piece consisting of a seamless tube, indented so as to form three tubes or channels, two of which are available for the passage of the wires to be joined and the other for the reception of the backwardly-bent ends of said wires, substantially as specified. 95

2. A joint-piece for electrical conductors, said joint-piece consisting of a seamless tube 100 having its sides indented so as to form three independent tubes arranged in triangular form, substantially as specified.

3. The combination of the joint-piece con-

sisting of three closely-bunched tubes, with conducting-wires one passing in one direction through one of said tubes and the other passing in the opposite direction through another of the tubes, the end portion of one wire being bent back into one end of the third tube and the end portion of the other wire being bent back into the opposite end of said third tube so as to form, at each end of the joint-piece, a loop of one wire through which

the other wire is passed and upon which it bears, substantially as specified.

In testimony whereof I have signed my name to this specification in the presence of two subscribing witnesses.

ELLWOOD IVINS.
